(57) **CLAIM**

The ornamental design for a belt buckle as shown and described.

DESCRIPTION

FIG. 1 is a perspective view of a belt buckle showing a closed configuration of our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a front view of the belt buckle in a closed condition shown in environmental use.

The broken lines in FIGS. 1-7 represent portions of the belt buckle that form no part of the claimed design. The other broken lines in FIG. 8 represent environmental subject matter only and form no part of the claimed design.

1 Claim, 5 Drawing Sheets
